(57) **CLAIM**

I claim the ornamental design for a chair, as shown and described.

DESCRIPTION

FIG. 1 is an upper perspective view of a chair; FIG. 2 is a rear perspective view of the design shown in FIG. 1; FIG. 3 is a front elevation view of the design shown in FIG. 1; FIG. 4 is a rear elevation view of the design shown in FIG. 1; FIG. 5 is a right side elevation view of the design shown in FIG. 1; FIG. 6 is a left side elevation view of the design shown in FIG. 1; FIG. 7 is a top plan view of the design shown in FIG. 1; and, FIG. 8 is a bottom plan view of the design shown in FIG. 1. The broken lines shown in the drawings are for the purpose of illustrating portions of the article that form no part of the claimed design. The shade lines shown represent surface shading and not surface ornamentation, color, or material type.

1 Claim, 8 Drawing Sheets
